John W. Odaniel

United States Patent Office.

JOHN W. ODANIEL, OF CLOVERDALE, INDIANA.

Letters Patent No. 98,097, dated December 21, 1869.

IMPROVEMENT IN HAY-ELEVATORS.

The Schedule referred to in these Letters Patent and making part of the same.

To all whom it may concern:

Be it known that I, JOHN W. ODANIEL, of Cloverdale, in the county of Putnam, and State of Indiana, have invented a new and useful Improvement on a Hay-Derrick; and I do hereby declare that the following is a full, clear, and exact description of the construction, and operation of the same, reference being had to the annexed drawings, making a part of this specification, in which—

Figure 1 is a perspective view.

Figures 2, 3, 4, 5, and 6, are sectional views.

The plan of my invention will be readily seen by referring to the drawings.

I construct my derrick on a very cheap scale, composed of plain, square timbers, of proportionate size, in dimensions to suit the farmer's use.

First, I take two pieces of timber, and frame them across each other, for sills. Second, four upright posts, with braces, to form a frame for the revolving beam. Third, a cap to the posts may be made of heavy timber, cutting the mortises for the posts diagonally across the grain of the wood, (or it may be made of cast-iron.) Fourth, one of the upright posts is framed so as to be taken out, and one part of the cap is detached, and made fast to this false post. This post is to be taken out when the derrick is wanted to be moved, in order to make it easily transported. When taken apart for moving, the derrick will be in five sections, as in the drawing, figs. 2, 3, 4, 5, and 6. The false post is fastened by means of pins at the foot, and by means of a lever-fastening at the top; and also a plate of iron, where the cap is wood, is fastened to the top of the false post, and may be used alone, for economy. Fifth, the upright revolving beam is framed with two firm braces, and has a pulley in each end of the beam for the fork-rope to run in.

I will now proceed to describe the operation of my invention.

The horse is hitched to the rope at *a*, in fig. 1. Any of the known hay-forks for derricks may be used, and are fastened to the rope at *b*. When ready to raise hay, the pulley *c* being fastened, by means of hook *d*, to an iron fastening, *e*, the slide-rope *f* is for the pul-

ley to slide on, and is fastened to the iron staples *e* and *e'*. The horse is now moved up, and pulls in the direction of *g*. When the hay is raised to the desired height, the hook *d* is thrown off its fastening. This lets the pulley *c* slide on the rope *f* to the staple *e'*, which causes the beam *E* to revolve around, bringing the fork, with hay, over the stack, which place is designated by the letter *i* in the drawing. Then, to bring the fork back to its first position, use the fall-rope *j*, which is used to drop the hay from the fork on the stack.

To take the derrick apart, draw the pins *k k k k*; raise the lever *l*, by rod *m*; carry the rod *m* around to *o*. The false post *C* and the upright revolving beam *H* will then come out, leaving the derrick in sections, as figs. 2, 3, 4, 5, and 6.

E H, fig. 2, represent the revolving upright and beam, when taken out.

In fig. 3, *l* and *m* represent the lever and rod, turned around, so as to let the beam out.

s, the cap.

F, fig. 4 represents the false post.

C, the plate-fastening of same.

r, the catch for lever-fastening.

F, fig. 5, the double pulley, which is marked by letter *c*, in fig. 1.

d, the hook on pulley.

F, fig. 6, one of the pins *k*.

What I claim as my invention, and desire to secure by Letters Patent, is—

1. The sills *A*, staples *K*, upright posts *B*, false post *C*, cap *s*, revolving beam *E*, catch-pulley *c*, the braces for upright posts *G*, and beam *H*, all combined and arranged substantially as specified.

2. The false post *C*, with metal plate and attachments, constructed as shown.

3. The hay-derrick, consisting of all the parts shown, and constructed, combined, and arranged as specified.

JOHN W. ODANIEL.
